UNITED STATES PATENT OFFICE

2,493,531

NOVELTY GARMENT

Gerald E. Fitches, Salt Lake City, Utah

Application April 20, 1948, Serial No. 22,104

2 Claims. (Cl. 2—115)

1

This invention relates to improvements in novelty garments, particularly shirts, dresses or other articles of wearing apparel where novel effects may be desired.

One object of the invention is to improve the ornamental effect obtained in a garment by variations in the appearance thereof particularly in obtaining changes in color by the combining of sections in novel effects.

This may be accomplished by detachably connecting the sections of the garment whereby a garment made of two sections for instance may have one section thereof replaced by another section of a different color, thereby producing novel and unusual effects in the garment. It is applicable especially to shirts which may be formed in two sections, either of which may be interchanged with a corresponding section of another shirt made in a different color. Thus, by providing two shirts of different colors, four novel effects may be obtained by interchanging the sections. The same idea may be applied in a blouse or skirt, resulting in an attractive effect.

A further object of the invention is to improve the construction and fastening of portions of the garment, particularly the cuff of the sleeve, by utilizing a slide fastener in combination with a snap fastener to obtain a closure thereof that is substantially invisible and may be opened or closed securely when desired.

Certain embodiments of the invention are illustrated in the accompanying drawings, in which:

Fig. 1 is a front perspective view of the invention applied to a shirt shown applied on a person;

Fig. 2 is a rear perspective view thereof;

Fig. 3 is a front perspective view of a collar and its fastening;

Fig. 4 is an enlarged perspective view of a fragment of the shirt sections and their fastening;

Fig. 5 is a fragmentary perspective view of a cuff construction on a shirt;

Fig. 6 is a perspective view of the shirt sections separated or detached;

Fig. 7 is a front elevation showing the invention applied to a skirt and blouse;

Fig. 8 is an enlarged perspective view thereof;

Fig. 9 is a diagrammatic view of the blouse showing the sections separated; and

Fig. 10 is a perspective view of the skirt from the side and showing the slide fasteners therefor.

The invention may be applied to different types of garments, some of which are illustrated in the drawings merely as representative of different

2

applications. In Figs. 1 to 6, inclusive, the invention is shown applied to a shirt made in two sections, although it is evident that any desired number of sections may be used for different ornamental effects.

The sections of the shirt are designated generally by the numerals 10 and 11 divided on a diagonal line that corresponds substantially with the line indicated at 14 in Figs. 1 and 2. As shown in Fig. 6, the sections 10 and 11 are entirely separable from each other, capable of complete detachment so that another section of corresponding construction may be substituted for either of these.

15 The detachable fastening of the sections may be accomplished by any suitable fastening means although it has been found preferable and desirable to use the usual form of slide fasteners, elements of which are illustrated at 12 and 13, comprising tapes containing guide members adapted to be connected together by a slider of the usual character. A fly or flap is adapted to overlap the juncture between the slide fastener, as designated generally at 14. When this flap 20 is closed and the slide fasteners connected throughout the entire length thereof, a substantially invisible seam results between the sections 10 and 11, which nevertheless may be rendered ornamental by disposing it diagonally over the shoulder of the garment in the form illustrated.

It will be evident that upon separation of the slide fastener elements 12 and 13 in detachable relation, different ornamental effects may be obtained. By the provision of two garments as an example of different ornamental effects or different colors as many as four changes can be provided by substituting a section of one color for that of another in the respective garments, replacing either of the sections in each garment 35 with the corresponding section in the other. This provides a highly ornamental and desirable novel effect which improves the ornamental character of the garment and its desirability for use.

The slide fasteners illustrated as an embodiment of one form of connection may be of the usual character capable of separation of the sections 10 and 11 at the ends of the slide fasteners, as illustrated in Fig. 4.

45 The garment may be provided with a collar, such as a sport collar or other suitable character, one form of which is shown in Fig. 3 and designated at 15. The collar opening does not extend throughout the height of the garment in this form but is adapted to be closed by a fastening such as a slide fastening, elements of which

are shown at 16 and 17, and to be closed by a cover flap 18. This slide fastening also may be of the usual character such as that described above.

While the shirt may be of the sport type in which short sleeves are provided, it is illustrated as having full length sleeves, as indicated at 19 in Fig. 5, with a cuff on the end thereof, shown at 19'. The cuff and lower portion of the sleeve are adapted to be closed by a slide fastener, elements of which are shown at 20 and 21, and closed by a flap 22. In addition to this slide fastener, a snap closure may be provided, as illustrated at 23 and 24. This snap fastener supplements the slide fastener by holding the flap 22 normally closed, although allowing its separation when it is desired to open the cuff by separating the slide fastener.

The invention is shown in Figs. 7 to 10, inclusive, as applied to a blouse and skirt, each of which has separable sections that may be replaced by other sections for novel ornamental effects.

Referring to Figs. 7 to 9, inclusive, the blouse is shown as formed of sections 25 and 26 divided on a line extending diagonally of the blouse as an example, although any desired form of separation therebetween may be used. These sections are connected together by separable fastenings which are illustrated as a slide fastening, elements of which are shown at 27 and 28 in Fig. 9. If the section 26 is open at the left side in Fig. 9 to facilitate the putting on or removal of this section or blouse, two separate slide fastenings may be used extending from the top to the bottom edge of the blouse.

Referring to Figs. 7, 8 and 10, the skirt is shown as formed of sections 29 and 30 detachably connected together by slide fasteners 33 and 34 illustrated in Fig. 10. These slide fasteners are adapted to be covered by flaps 31 and 32 and to extend diagonally downwardly in the manner illustrated in Figs. 8 and 10. The section 30 is shown as a removable panel which may be replaced on the section 29 for novel ornamental appearance by substituting a different colored panel therefor.

It will be evident that the invention may be applied to other articles of clothing of which these are illustrated as examples and by means of the replacement of different sections with other sections of different colors or other effects, novel results may be obtained with very few parts.

While the invention has been illustrated and

described in certain embodiments, it is recognized that variations and changes may be made therein without departing from the invention except as specified in the claims.

5 I claim:

1. A garment comprising a body portion including a plurality of sections separable from each other on a line extending substantially diagonally of the body portion throughout the height thereof, said separating line having its length extending from and through the lower margin of the front panel diagonally upwardly through such panel over a shoulder and thence diagonally downward through the rear panel to and through the lower margin thereof to thereby present a pair of sections completely separable on such dividing line, and disengageably separable fastening means connecting the sections to each other and permitting replacement of one section by a corresponding section of a different ornamental appearance.

2. A waist garment ensemble comprising a plurality of sections each fashioned to include a linear contour adapted to co-operate with the linear contour of a complementary section in completing the garment, such combined linear contours forming a separable division line extending from and through the lower margin of the front panel of the garment diagonally upward to and over a shoulder and thence diagonally downward through the rear panel to and through the lower margin of such rear panel, such linear contour portions carrying elements of separable fastening means for detachably securing complementary sections together to complete such division line and to thereby complete the garment solely by assembling such complementary sections on such division line, said ensemble permitting interchangeability of sections at will by replacing a section with a section of similar contour.
